**5,5-DIOXODIBENZO[1,2,5]THIADIAZEPINES
 DERIVATIVES AND METHOD OF USE**

Abraham Weber, Paris, France, assignor to Mead Johnson & Company, Evansville, Ind., a corporation of Indiana

No Drawing. Filed Dec. 6, 1963, Ser. No. 328,460
 13 Claims. (Cl. 167—65)

The present invention is concerned with compounds having the following structure and acid addition salts thereof.

FORMULA I

These substances are novel organic compounds comprising a new class of heterocyclic products known as the 5,5-dioxodibenzo[1,2,5]thiadiazepines. The various positions of this tricyclic nucleus are numbered as shown in the formula.

The substituent groups R³ and R⁹ are attached to the respective benzene rings in the 1, 2, 3, 4, or in the 7, 8, 9, or 10 positions as is indicated. R³ represents from one to two substituents which are selected from the following: hydrogen, halogen, methyl, trifluoromethyl, alkoxy, alkylthio, and alkylsulfonyl, each having up to four carbon atoms. R⁹ is hydrogen, halogen, methyl, trifluoromethyl, dimethylsulfamyl, dimethylamino, carbalkoxy, alkylthio, alkylsulfonyl, alkoxy, or alkanoyl, each of which may contain up to four carbon atoms. R⁶ is lower alkyl having up to four carbon atoms, or benzyl.

The group

as a whole refers to an amino-substituted alkyl side chain. Alk is an alkylene group having two to four carbon atoms which is attached to the nitrogen atom in the 11-position of the dioxodibenzothiadiazepine nucleus and separates the amino group of the side chain therefrom by two or three carbon atoms. In other words, Alk is an ethylene or trimethylene group which may be further substituted by a methyl or ethyl group.

The amino substituent

which is attached to the Alk group is pyrrolidino, piperidino, morpholino, thiomorpholino, or 4-R⁴-piperazino in which R⁴ is alkyl, or hydroxyalkyl having up to four carbon atoms, or an ester thereof with an alkanoic acid having one to three carbon atoms, or it is a tertiary amino group in which R¹ is alkyl or hydroxyalkyl having up to four carbon atoms or an ester thereof with an alkanoic acid having one to three carbon atoms, and R² contains up to four carbon atoms and is alkyl.

The preferred compounds of the present invention include the pharmaceutically acceptable acid addition salts of those in which the benzo substituents R³ and R⁹ are hydrogen, R⁶ is methyl, and Alk is trimethylene, and

2

R¹ and R² are alkyl containing up to four carbon atoms.

The compounds of Formula I are prepared by reaction of an aminoalkyl ester such as a chloride, bromide, iodide, methanesulfonate, p-toluenesulfonate, sulfate, carbonate, etc. of the formula

wherein X is chlorine, bromine, iodine, p-C₆H₄SO₃—, CH₃SOC—, SO₄—, —OCO₂—, C₂H₅OCO₂—, etc., with a corresponding dioxodibenzothiadiazepine of the above formula bearing a hydrogen atom in the 11-position according to the following scheme:

The condensation illustrated by this equation is preferably carried out under anhydrous conditions employing an inert solvent as reaction medium. A strong base is required as condensing agent in carrying out this process and elevated temperatures of the order of 80–200° C. assist in bringing reaction to completion within a convenient period of time.

The strong alkali metal bases such as the oxides, alkoxides, hydrides, alkyls, aryls, and amides are preferred as condensing agents. It is thought that the acidic hydrogen in the 11-position of the dioxodibenzothiadiazepine ring is first neutralized with the formation of the alkali metal salt which then reacts with the aminoalkyl ester. Alkali metal salt-forming reagents suitably serve as condensing agents and include sodium amide, lithium amide, sodium hydride, butyl lithium, potassium t-butoxide, phenyl lithium, etc. If desired, the alkali metal salt of the dioxodibenzothiadiazepine reactant may be prepared as a separate preliminary step before carrying out the reaction with the aminoalkyl ester. A further quantity of condensing agent in addition to that used to form the alkali metal salt is not then required.

The dioxodibenzothiadiazepine reactants referred to in the above scheme are prepared by means of a four-step process which is referred to in my copending application Serial No. 328,476, filed herewith. In general terms, the steps involved in the process are:

- (1) Reaction of an o-bromoaniline with an o-nitrobenzenesulfonfonyl halide to form a 2-nitro-2'-bromobenzene-sulfonanilide.
- (2) Alkylation at the sulfonamide nitrogen atom to introduce the R⁶ group.
- (3) Reduction of the 2-nitro group to a 2-amino group, and preferably acylation thereof.
- (4) Ring closure.

The compounds of the present invention are useful as psychotropic agents and muscle relaxants having low toxicities and remarkable freedom from side effects. They

may be administered orally or parenterally in doses in the range 0.1 to 100 mg./kg.

6-methyl - 11 - (3-dimethylamino-1-propyl)-5,5-dioxodibenzo[1,2,5]thiadiazepine hydrochloride, a preferred product of the present invention, is classed as an anti-depressant drug which possesses an excitant component differing from that of amphetamine in that it has little tendency to cause motor stimulation. It has an oral LD₅₀ in the mouse in excess of 200 mg./kg., no deaths having occurred at this dosage. The intraperitoneal LD₅₀ is approximately 198 mg./kg., but signs of excitement and muscle relaxation are apparent at intraperitoneal doses of 12.5 mg./kg. or less. This substance has an oral ED₅₀ in preventing reserpine ptosis in the mouse of 1.5 mg./kg., and while eliciting excitant signs at this dose, it fails to reverse reserpine ptosis in the mouse at doses four times larger. Reversal of reserpine ptosis is characteristic of conventional central nervous stimulants such as amphetamine. The ability to prevent reserpine ptosis is a character of pharmaceuticals of established clinical utility as anti-depressants. The excitant character of the product is further differentiated from that of amphetamine in that increased toxicity thereof is not observed when treated mice are grouped rather than housed singly. The product is about equivalent to imipramine in antagonizing i.v. histamine induced bronchoconstriction in the guinea pig employing a modified procedure of Lands, et al., J. Pharmacol. Exp. Therap. 95, 45 (1949).

The following examples are provided to further illustrate the manner of practicing the present invention. They are not to be considered the sole embodiments thereof, however, and are provided only for illustrative purposes.

Example 1.—6-methyl-11-(2-diethylaminoethyl)-5,5-dioxodibenzo[1,2,5]thiadiazepine hydrochloride.—A mixture of 19.5 g. (0.075 mole) of 6-methyl-5,5-dioxodibenzo[1,2,5]thiadiazepine and 170 ml. of dry dimethylformamide, which serves as liquid reaction medium, is warmed to 100° C. in a reaction vessel equipped with a thermometer, stirrer, and reflux condenser and for exclusion of atmospheric moisture. A suspension of 10.5 g. (0.225 mole) of sodium hydride in mineral oil is then added portionwise in order to avoid an unduly violent exothermic reaction. The yellow suspension of the sodium salt of the thiadiazepine reactant which forms is treated with 35 g. (0.150 mole) of 2-diethylaminoethyl bromide hydrobromide during a 10 min. period while maintaining the temperature in the range 100–120° C. The suspension is agitated while heating is continued at 115–120° C. for 3 hrs. It is then cooled to room temperature, poured into ice water, and the white precipitate collected. It is dissolved in dilute hydrochloric acid, insoluble material removed by filtration, and the filtrate neutralized to pH 9.0 with concentrated sodium hydroxide, resulting in precipitation of the desired product as the

free base. The precipitate is collected, dissolved in isopropanol, and treated with slightly more than one molecular proportion of hydrochloric acid, resulting in precipitation of the hydrochloride salt of the desired product as a white powder, M.P. 217–219° C. The material is recrystallized from isopropanol to afford the purified hydrochloride salt as clusters of white needles, M.P. 223–224° C.

Analysis.—Cl, 8.73; N, 10.54; S, 8.15.

This substance has a water solubility of 19 mg./ml. A 1% aqueous solution thereof has pH 5.4. On neutralization to pH 7.0, no precipitate forms.

Example 2.—6-methyl - 11 - (3-dimethylaminopropyl)-5,5 - dioxodibenzo[1,2,5]thiadiazepine hydrochloride.—The procedure of Example 1 is repeated, substituting 24 g. (0.16 mole) of 3-dimethylamino-1-propyl chloride hydrochloride for the 2-diethylaminoethyl bromide reactant specified in that example. A reaction period of 6 hrs. at 90–95° C. is employed. The free base form of the product is recovered as specified in Example 1 and the final product is converted to the hydrochloride salt and recrystallized from isopropanol as stated, M.P. 199–200° C.

Analysis.—Cl, 9.01; N, 10.95; S, 8.40.

This material has a water solubility of 800 mg./ml. A 1% solution thereof has pH 5.5 and no precipitation occurs on adjusting such solution to pH 7.0.

Other alkali metal salt-forming reagents may be substituted on a chemical equivalent basis for sodium hydride in Examples 1 and 2. For instance, substantially similar operation and results follow from the use of sodium amide, lithium amide, butyl lithium, sodium triphenylmethyl, or potassium t-butoxide in those procedures.

Examples 3–36—Synthesis of additional structural variants.—The procedures of Examples 1 and 2 are adapted to synthesis of the products listed in the following table from the aminoalkyl halide and dioxodibenzo-thiadiazepine reactants listed when substituted on a molecular equivalent basis. The products are most readily purified as acid addition salts such as the hydrochloride, hydrobromide, sulfate, phosphate, methanesulfonate, or p-toluenesulfonate salts. Since the compounds are all relatively strong bases, salts of the products with a great variety of acids may be formed including those of carboxylic acids such as acetic, propionic, benzoic, tartaric, citric, mucic, maleic, and glutamic acid, organic and sulfonic and sulfuric acids such as methane, ethane, and benzene sulfonic acids, lauryl sulfuric acid, etc. In those instances where stereoisomers exist due to asymmetry in the molecule, salts with optically active acids may be formed for the purpose of separating the resulting diastereometric salts. For pharmaceutical purposes, salts with non-toxic acids having pharmaceutically elegant physical properties are preferred.

*Hydrochloride salt; slightly hygroscopic white powder, M.P. 222-223° C.; water solubility 1 g./ml.; 1% aqueous solution exhibits pH 4.5 from which a precipitate forms on neutralization to pH 7.0.

Analysis.—C, 55.36; H, 0.04; N, 11.26; S, 8.83.

Example 37—Parenteral solution.—A solution for injection is prepared as follows: 6-methyl-11-(3-dimethylamino-1-propyl)-5,5-dioxodibenzo[1,2,5]-thiadiazepine hydrochloride, 500 g., is dissolved in 9 l. of water for injection, U.S.P. The solution is adjusted to pH 7.0 with dilute aqueous sodium hydroxide, diluted to 10 l. and filtered sparkling clear. It is then filled into 1 ml. glass ampoules, the ampoules sealed, and sterilized by heating in an autoclave at 121° C. for 15 min.

Example 38—Tablets.—A dry blend of 165 g. of lactose, U.S.P. and 1.0 g. of acacia powder, U.S.P., is prepared and granulated with a 10% w./w. starch paste containing 3.0 g. of corn starch, U.S.P. The moist granulation is screened through No. 12 screen, and dried at 130° F. until the moisture is less than 2%. The dry granules are then reduced in size by passage through a No. 20 screen and the following materials are thoroughly blended with the screened granulation:

	G.
6 - methyl - 11 - (3 - dimethylamino - 1 - propyl) - 5,5 - dioxodibenzo[1,2,5]thiadiazepine hydrochloride	25.0
Talc	4.0
Stearic acid, powdered	2.0

The resulting blend is then compressed into tablets, each containing 25.0 mg. of active ingredient.

The preceding dosage forms are suitable for use in 70 human beings. Doses in the range of 40 mg. to 300 mg. per day may be employed, but in any event the precise dose is to be selected by the physician.

Example 39—2-methoxy-6-methyl-11-[4-(2-hydroxyethyl)piperazino]ethyl-5,5-dioxodibenzo[1,2,5] 75

thiadiazepine hydrochloride.—A mixture of 0.4 g. of sodium hydroxide, 20 ml. of water, 20 ml. of dioxane, and 4.88 g. of the product of Example 6 is agitated at room temperature overnight. The mixture is then poured into 100 ml. of water, the insoluble material removed by filtration, dissolved in isopropanol, and treated with hydrogen chloride, resulting in precipitation of the desired product.

While several particular embodiments of this invention are shown above, it will be understood that the invention is not to be limited thereto, since many modifications may be made, and it is contemplated by the appended claims to cover any such modifications as fall within the true spirit and scope of the invention.

What is claimed is:

1. A compound selected from the group having the formula and the acid addition salts thereof

wherein

R³ is from one to two substituents selected from the group consisting of hydrogen, halogen, methyl, trifluoromethyl, alkoxy, alkylthio, and alkylsulfonyl and contains up to four carbon atoms;

R^6 is selected from the group consisting of lower alkyl having one to four carbon atoms, and benzyl;

R^9 is selected from the group consisting of hydrogen, halogen, methyl, trifluoromethyl, dimethylamino, dimethylsulfamyl, carbalkoxy, alkylthio, alkylsulfonyl, alkoxy, and alkanoyl, and contains up to four carbon atoms;

Alk is selected from the group consisting of ethylene and trimethylene having up to one alkyl substituent containing up to two carbon atoms;

is selected from the group consisting of pyrrolidino, piperidino, morpholino, thiamorpholino, 4- R^4 -piperazine, and amino wherein

R^1 and R^4 are selected from the group consisting of alkyl, hydroxyalkyl having up to four carbon atoms and alkoxyalkyl having up to seven carbon atoms, and

R^2 contains up to four carbon atoms and is alkyl.

2. The compound of claim 1 wherein R^3 and R^9 are hydrogen, R^6 is methyl, Alk is ethylene, R^2 is alkyl having up to four carbon atoms, and R^1 is alkyl having up to four carbon atoms.

3. The compound of claim 1 wherein R^3 and R^9 are hydrogen, R^6 is methyl, Alk is trimethylene, R^2 is alkyl having up to four carbon atoms, and R^1 is alkyl having up to four carbon atoms.

4. The compound of claim 1 wherein R^3 and R^9 are hydrogen, R^6 is methyl, Alk is ethylene bearing a methyl substituent, and R^1 and R^2 are each alkyl having up to four carbon atoms.

30

35

5. 6 - methyl - 11 - (3 - dimethylamino - 1 - propyl)-5,5-dioxodibenzo[1,2,5]thiadiazepine.

6. 6 - methyl - 11 - (2 - diethylamino - 1 - ethyl)-5,5-dioxodibenzo[1,2,5]thiadiazepine.

7. 6 - methyl - 11 - (2 - dimethylamino - 1 - ethyl)-5,5-dioxodibenzo[1,2,5]thiadiazepine.

8. The therapeutic process which comprises administering to a mammalian host a dose of from 0.1 mg. to 100 mg. of a compound claimed in claim 1 per kilogram of body weight of said host.

9. A pharmaceutical composition in dosage unit form adapted for administration to a mammalian host comprising a pharmaceutical carrier and sufficient of a compound claimed in claim 1 to provide a daily dose of from 0.1 mg. to 100 mg. thereof per kilogram of body weight of said host.

10. A pharmaceutical composition in dosage unit form comprising from 40 to 300 mg. of a compound selected from the group consisting of 6-methyl-11-(3-dimethylamino-1-propyl)-5,5-dioxodibenzo[1,2,5]thiadiazepine and the pharmaceutically acceptable acid addition salts thereof and a pharmaceutical carrier therefor.

11. 6 - methyl - 11 - (3 - dimethylamino - 1 - propyl)-5,5-dioxodibenzo[1,2,5]thiadiazepine hydrochloride.

12. 6 - methyl - 11 - (2 - diethylamino - 1 - ethyl)-5,5-dioxodibenzo[1,2,5]thiadiazepine hydrochloride.

13. 6 - methyl - 11 - (2 - dimethylamino - 1 - ethyl)-5,5-dioxodibenzo[1,2,5]thiadiazepine hydrochloride.
